UNITED STATES PATENT OFFICE.

ARTHUR V. KINSEL, OF LOS ANGELES, CALIFORNIA.

SPARK-PLUG.

1,349,158.

Specification of Letters Patent. Patented Aug. 10, 1920.

Application filed June 17, 1919. Serial No. 304,930.

To all whom it may concern:

Be it known that I, ARTHUR V. KINSEL, a citizen of the United States, residing at Los Angeles, in the county of Los Angeles and State of California, have invented new and useful Improvements in Spark-Plugs, of which the following is a specification.

My object is to make a double gap spark plug, and my invention consists of the novel features herein shown, described and claimed.

Figure 1 is a view in elevation of a double gap spark plug embodying the principles of my invention.

Fig. 2 is a vertical diametrical longitudinal sectional detail as on the lines 2—2 of Figs. 1 and 3 and looking in the direction indicated by the arrows.

Fig. 3 is a bottom plan looking in the direction indicated by the arrow 3 in Fig. 2.

The metallic casing 1 comprises the head 2 having an internal screw threaded bore 3 extending downwardly from its upper end, a neck 4 extending downwardly from the head 2 and having an internal packing seat 5, the rim 6 extending downwardly from the neck 4, the neck 7 extending downwardly from the rim 6, the externally screw threaded nipple 8 extending downwardly from the neck 7, and the housing 9 extending downwardly from the screw threaded nipple 8, there being a straight bore 10 from the seat 5 downwardly through the portions 6, 7, 8 and 9 and lateral openings 11 and 12 extending crosswise of the bore 10 through the housing 9, and there being a secondary core seat 13 in the housing 9 at the lower end of the bore 10 and an internal screw thread 14 in the lower end of the housing 9 below the seat 13, and there being a secondary casing 15 extending downwardly in line with the housing 9 and having an externally screw threaded nipple 16 fitting the threads 14.

Gaskets 17 fit the seat 5, the main insulator 18 has an enlarged portion 19 fitting against the gaskets 17, a reduced portion 20 extending downwardly in the bore 10 nearly to the level of the tops of the lateral openings 11 and 12, and a reduced portion 21 extending upwardly from the enlarged portion 19 and having a neck 22 near its upper end, there being a central opening 23 extending from the upper end face 24 to the lower end face 25.

The conductor wire 26 is inserted down-

wardly through the opening 23 and has a sparking end 27 below the end face 25. Gaskets 28 fit the upper part of the enlargement 19, and a gland 29 is screwed down into the threads 3 against the gaskets 28 to hold the insulator 18 firmly in the casing 1. A cap 30 fits the end face 24 and the edge 31 of the cap is spun into the annular recess around the neck 22. The central portion of the cap 24 fits against the head 32 of the wire 23 and the screw threaded nipple 33 extends upwardly from the center of the cap for the attachment of the wire.

The secondary insulator 34 fits the seat 13 in the housing 9, a secondary conductor 35 extends through the center of the secondary insulator 34 and has a sparking end 36 adjacent to the sparking end 27, and a sparking end 37 upon its lower end. The fourth sparking end 38 is formed upon the conductor 39 and the fourth sparking end is mounted in opposition to the third sparking end 37. The conductor 39 comprises the sparking end 38, the straight vertical portion 40 extending downwardly from the sparking end 38, the bend 41 extending from the lower end of the portion 40, the inclined arm 42 extending outwardly from the bend 41, and the straight portion 43 extending through the secondary casing 15 and rigidly fixed in the casing.

A spark gap 44 is formed between the sparking ends 27 and 36, and a second spark gap 45 is formed between the sparking ends 37 and 38 thus producing a double spark gap in a single line of conductivity. The spark gap 44 is in the chamber 10 and communicates with the explosive mixture in the cylinder through the openings 11 and 12. The spark gap 45 is in the chamber 46 below the secondary insulator 34 and within the secondary casing 15 and communicates with the explosive mixture through the open lower end of the chamber 46.

Various changes may be made without departing from the spirit of my invention as claimed.

I claim:

A spark plug comprising a metallic casing, a main insulator mounted in the metallic casing its inner end terminating at a proper point within the casing, a conductor rod mounted centrally through the main insulator its inner end extending from the end of the main insulator, a second insulator fixed in a recess within the end of the cas-

ing opposite the inner end of the main insulator having a conductor rod through the center thereof, its inner end positioned within proper sparking distance of the inner 5 end of the rod of the main insulator there being a chamber formed between the two insulators and there being ports cut through the wall of the metallic casing communicating with the chamber, means for holding 10 the second insulator in place, and a third

conductor rod connected with the metallic casing and having its free end disposed within sparking distance of the outer end of the conductor rod in the second insulator thereby forming two spark gaps within the 15 plug in a sparking circuit.

In testimony whereof I have signed my name to this specification.

ARTHUR V. KINSEL.
